BRYAN M. MILLER, OF WASHINGTON, DISTRICT OF COLUMBIA

OXY-ACETYLENE BURNER

Application filed June 17, 1931. Serial No. 545,123.

This invention relates to oxy-acetylene torches or burners and has for an object to provide a burner which may be used for long periods of time to remove paint, rust, etc., 5 from large structures, such as bridges, railway coaches and cars, etc., without back firing.

The usual type of oxy-acetylene burner used in cutting bars, rails and the like is capable of use only for short periods and then must be laid aside to cool. This renders such a burner useless for continuous use for many hours, since it is well-known that the heat of the flame creeps back along the jet block, 10 causing a cherry red glow to be visible, which eventually reaches the manifold or chamber integral with the back of the jet block and ignites the mixture, causing back firing, after 15 which the burner must be allowed to cool 20 before further use.

I have discovered that if the jet block is formed of one block of metal, which constitutes one wall of the manifold, and if the remaining walls of the manifold are formed 25 of a separate plate or plates of metal, welded or otherwise secured to the jet block, the union between the two different metals will be sufficiently imperfect to retard, if not in most instances actually prevent, the conduction 30 of heat back through the jet block to the manifold, so that back firing is positively eliminated, and thus the tool may be used continuously for hours on a large structure, 35 while, at the same time, the welding of the metals together is sufficient to unite and bond the metals together so that leakage will not occur.

One embodiment of carrying the above 40 outlined principle into effect is illustrated in the accompanying drawing and described in the following specification, it being understood that various modifications may be resorted to within the scope of the appended 45 claims without departing from the spirit or sacrificing any of the advantages of the invention.

In the accompanying drawing forming 50 part of this specification,

Figure 1 is a perspective view of an oxy-

acetylene burner constructed in accordance with my invention,

Fig. 2 is an enlarged cross sectional view taken on the line 2-2 of Fig. 1,

Fig. 3 is an enlarged longitudinal sectional view taken on the line 3-3 of Fig. 2,

Fig. 4 is a fragmentary perspective detail view showing the jet block and the separate plates which coact with the jet block in forming the manifold, and

Fig. 5 is a fragmentary sectional view showing a modified form of the invention, in which a single plate coacts with the jet block in forming the manifold.

Referring now to the drawing in which like characters of reference designate similar parts in the various views, 10 designates the usual tubular handle having at the rear end valved connections 11 and 12 for the admission of oxygen and acetylene gas. The front end of the handle is equipped with the usual tubular stem 13 having the usual air valves 14 and terminating in an abruptly bent outlet nozzle 15. These parts are of the usual and well-known type.

In carrying out the invention, I provide a jet block 16 which preferably is formed of a single block of metal of substantially oblong longitudinal section and cross section, and of relative great width with respect to its length as best shown in Figs. 2 and 3, the block preferably being perforated transversely along the central plane thereof to provide minute long jet passages 17 corresponding in length to the width of the block and which open through the front face 18 and rear face 19 of the block. Adjacent the rear face 19, the block is beveled on each side, as shown at 20.

Preferably, I provide a manifold for the jet block consisting of a pair of plates 21, as best shown in Figs. 2 and 4. These plates may be formed of the same metal as the jet block and are relatively thin. The plates are placed against the beveled faces 20 of the jet block and thus converge and meet at a point in alignment with the row of jet passages at a short distance beyond the inner end face 19 of the jet block, as best shown in Fig. 2. The plates are perforated at the

central point of their meeting edges to receive the nozzle 15. The meeting edges of the plates are welded together and to the nozzle, as shown at 22. The edges of the 5 plates which lie along the beveled faces 20 of the jet block are welded to the jet block, as shown at 23. By welding, I, of course, include brazing, sweating, or any equivalent method of bonding the plates together and 10 to the jet block and nozzle. Preferably, the ends of the plates 21 are sealed together and sealed to the ends of the jet block by the use of enough of the welding material to seal the spaces between the plates and block, as best 15 shown at 24 in Figs. 1 and 3.

It is now clear that the plates 21 coact with the rear face 19 of the jet block in forming a manifold transversely and connecting all of the jet passages 17, and that such manifold 20 is substantially triangular in outline and is of relatively small size so that, in practice, the manifold affords no more than a passage for the combustible fluid, being of insufficient volumetric capacity to afford any appreciable accumulation of large volumes of combustible fluid in the manifold.

In Fig. 5, there is shown a modified form of manifold, in which I employ a single arched plate 25 of metal, to coact with the 30 rear face 26 of the perforated jet block 27 in forming the manifold, the supply nozzle 28 of the burner entering the crown of the plate at a central point, as above described. In this modified form of the invention, also, 35 the nozzle is bonded to the plate by welding, as shown at 29, and also the edges of the plate are bonded to the beveled faces 30 of the jet block by welding, as shown at 31. The spaces at the ends of the plate are sealed by 40 plugs of welding material 32, as above described.

In both the preferred form of the invention and in the modified form of the invention, it will be seen that the manifold is 45 formed by a separate plate or plates of metal which coact with the rear face of the jet block adjacent the beveled sides of the block in forming the manifold. Furthermore, it will be observed that the manifold in both 50 instances is no more than a transverse passage for the combustible fluid and is of restricted area so as to prevent accumulation of large volume of the fluid in the manifold.

In practice, as above stated, it has been 55 found that an oxy-acetylene burner, constructed as above described, can be used continuously for hours without conduction of heat from the burner block to the manifold sufficient to cause back firing. Consequently, 60 the tool may be used in removing paint and rust and other material from structures such as steel bridges, wood and steel railway coaches and cars, as well as other structures which have considerable exposed area.

65 By referring now to Fig. 3, it will be seen

that a substantially triangular baffle 33 is disposed in the end of the nozzle 15 in both forms of the invention, the sides of the baffle, as shown, performing the function of deflecting the incoming combustible fluid longitudinally toward the ends of the manifold so that the pressure throughout the manifold will be equalized on the jet passages 17. Otherwise, without this baffle, the pressure on the jet passages directly in alignment with the nozzle might be greater than those nearer the ends of the nozzle.

70 From the above description it is thought that the construction and operation of my invention will be understood without further 80 explanation.

Having thus described the invention, I claim:

1. An oxy-acetylene burner comprising a 85 tubular handle for supplying a combustible fluid, a jet block of relatively great width with respect to its length having long jet passages corresponding in length to the width of the block and opening through the front and rear wall of the block, the sides 90 of the block being tapered near the rear wall to provide a rear wall of small area, a sheet metal manifold having diverging portions engaging the tapered faces of the jet block and extending beyond the rear face of the jet 95 block and coacting with said rear face in connecting all the intake ends of the jet passages of the block, and means for connecting said tubular handle to said manifold.

2. An oxy-acetylene burner comprising a 100 solid metal jet block having a longitudinal central row of long jet passages corresponding in length to the width of the block and opening through the front and rear faces of the block, said jet block being of relatively 105 great width with respect to its length and having the sides tapered contiguous to said rear face of the block to restrict said rear face to a small superficial area, a pair of inclined sheet metal plates bonded to the tapered faces of the jet block and being bonded together at their longitudinal meeting edges beyond said rear face, said plates coacting 110 with said rear face in forming a manifold of substantially triangular cross section connecting all of said jet passages and of small diameter to prevent accumulation of large 115 volume of the combustible fluid in the manifold, and a hollow handle carried by said manifold for supplying a combustible fluid to 120 said manifold.

3. An oxy-acetylene burner comprising a 125 jet block of relatively great width with respect to its length having a longitudinal row of long jet passages corresponding in length to the width of the jet block and opening through the front and rear faces of the block, the sides of the block being tapered contiguous to the rear face thereof to provide a 130 rear face of relatively small area, an arched

sheet metal manifold of different metal than
the jet block having the sides thereof dis-
posed obliquely and bonded to said beveled
faces of the jet block and having the crown
5 thereof extending over said rear face of the
jet block in close proximity thereto and form-
ing a manifold of relatively small diameter
connecting all of said jet passages, and a tu-
bular handle for a combustible fluid passing
10 through an opening in the crown of said
arched manifold.

In testimony whereof I affix my signature.
